CLAIM

The ornamental design for a table, as shown and described.

DESCRIPTION

FIG. 1 is a front perspective view of a table embodying the new design;

FIG. 2 is a front view, the rear view being a mirror image thereof;

FIG. 3 is a right side view, the left side being a mirror image thereof;

FIG. 4 is a top view thereof; and,

FIG. 5 is a bottom view thereof.

In the drawings, the broken lines show portions of the table that form no part of the claimed design.
